UNITED STATES PATENT OFFICE.

CHARLES WESLEY RANDALL, OF WEST HOBOKEN, NEW JERSEY.

FLY-PAPER HOLDER.

1,217,825.

Specification of Letters Patent. Patented Feb. 27, 1917.

Application filed November 16, 1916. Serial No. 131,658.

To all whom it may concern:

Be it known that I, CHARLES W. RANDALL, a citizen of the United States, and a resident of West Hoboken, in the county of 5 Hudson and State of New Jersey, have invented a new and Improved Fly-Paper Holder, of which the following is a full, clear, and exact description.

This invention relates to a fly paper holder but it is not limited to this use as 10 the device is suitable as a stretcher for holding any article in stretched relation, as for instance, lace curtains.

The invention has for its general objects 15 to provide a holding frame of simple, novel and inexpensive construction which effectively holds a strip of fly paper stretched flat with the frame protecting the paper, so that it cannot come in contact with other 20 articles or be torn, and the frame forms a convenient means for enabling the paper to be leaned against or hung on a wall in vertical position, or enables it to lie flat on a table or other support.

25 A more specific object of the invention is the provision of a frame or holding device having novel means for clamping the ends of the fly paper or article in the frame, one of the clamping means being adjustable to 30 ward the other for adapting the device for fly paper or articles of different sizes.

With such objects in view, and others which will appear as the description proceeds, the invention comprises various novel 35 features of construction and arrangement of parts which will be set forth with particularity in the following description and claims appended hereto.

In the accompanying drawing, which 40 illustrates one embodiment of the invention and wherein similar characters of reference indicate corresponding parts in all the views,

Figure 1 is a perspective view of the device lying flat and supporting a fly paper; and

Figs. 2 and 3 are detail sectional views taken respectively on the lines 2—2 and 3—3, Fig. 1.

50 Referring to the drawing, A designates the frame or holder in which is clamped or stretched a strip of fly paper B, or other article. The frame A comprises side bars 1 and 2 and cross bars 3 and 4. These bars 55 3 and 4 have longitudinal grooves 5 and 6 into which clamping strips 7 and 8 are

forced with the ends of the fly paper disposed under the clamping strips so that they will be forced into the grooves 5 and 6. The cross pieces 3 and 4 are connected with the 60 side bars 1 and 2 by corner blocks 9 and 10, which have recesses 11 and 12 in their inner faces for receiving the ends of the bars 3 and 4, respectively. The bars 3 and 4 do not extend fully into the recesses and the 65 blocks, so that passages 13 and 14 are provided for the side strips 1 and 2 to pass longitudinally through the blocks. The blocks 9 are rigidly fastened to the side strips 1 and 2 and the cross bar 3 is rigidly 70 fastened to the blocks 9, but while the cross bar 4 is rigidly fastened to the blocks 10, the side bars 1 and 2 pass loosely through the blocks 10, so that the cross bar 4 can be adjusted toward and from the cross bar 3 to 75 thereby vary the effective length of the frame or holder. The clamping strips are long enough to fit into recesses 15 and 16 in the top faces of the blocks 9 and 10. The side bars 1 and 2 are each provided with a 80 series of notches or recesses 17, and by adjusting the blocks 10 longitudinally of the strips 1 and 2, the recesses 16 of the blocks can be brought into registry with any recess in the strips 1 and 2, so that the clamping 85 bar 8 can be forced into the recesses 17 to hold the blocks 10 as well as the cross bar 4 in adjusted position. Thus the clamping bar 8 performs two functions; that of 90 clamping one end of the article B, and that of holding the adjustable bar 4 in fixed position with respect to the side bars 1 and 2.

From the foregoing description taken in connection with the accompanying drawing, the advantages of the construction and 95 method of operation will be readily understood by those skilled in the art to which the invention appertains, and while I have described the principle of operation, together with the device which I now consider to be the best embodiment thereof, I 100 desire to have it understood that the device shown is merely illustrative and that such changes may be made when desired as fall within the scope of the appended claims. 105

Having thus described my invention, I claim as new and desire to secure by Letters Patent:

1. A holder of the class described comprising side bars, cross bars, blocks fastened to 110 the ends of the cross bars, the side bars being rigidly fastened to one pair of the blocks

and slidable in the other pair, means for clamping an article to one of the cross bars, and means for clamping an article to the other cross bar and also clamping the blocks 5 of said cross bar to the side bars.

2. A holder of the class described comprising a frame consisting of side bars, a cross bar having a longitudinal groove, blocks on the ends of the said cross bar and through

which the side bars slide, said blocks having 10 recesses disposed in line with the said groove, and the side bars having a plurality of recesses, and a clamping strip adapted to wedge into the groove and to engage in the recesses of the said blocks and side bars. 15

CHARLES WESLEY RANDALL.
